Term of patent 14 years

Int. Cl. D7—03

U.S. Cl. D7—137

FIG. 1

FIG. 2

FIG. 3

FIG. 1 is a top plan view of a salad fork or the like showing my new design;

FIG. 2 is a bottom plan view thereof; and

FIG. 3 is a side view thereof.

The characteristic feature of my design resides in the combination of a salad fork or the like having a scoop-like handle portion, blunt rounded tines and handle edges of substantially planar configuration along their longitudinal extent.

I claim:

The ornamental design for a salad fork or the like, substantially as shown and described.
